UNITED STATES PATENT OFFICE.

THOMAS B. VAN PELET, OF CARTERVILLE, MISSOURI.

WATER-WHEEL.

SPECIFICATION forming part of Letters Patent No. 241,761, dated May 17, 1881.

Application filed January 25, 1881. (Model.)

To all whom it may concern:

Be it known that I, THOMAS B. VAN PELET, a citizen of the United States, formerly residing at Augusta, in the county of Butler and State of Kansas, but now residing in Carterville, Jasper county, Missouri, have invented a new and useful Counter Spiral Current or Dam Water-Wheel, of which the following is a full, clear, and exact description, reference being had to the annexed drawings and letters of reference marked thereon, in which—

Figure 1 is a perspective view of a shaft carrying two or more of my improved water-wheels. Fig. 2 is a view of the flume provided with inclined counter-buckets, and Fig. 3 is a top view of the lower half of the flume and the shaft carrying the water-wheels.

Similar letters indicate like parts in both figures.

20 My invention relates to improvements in water-wheels; and it consists in the peculiar construction of two or more water-wheels mounted on the same horizontal shaft and revolving in a flume provided with stationary counter-buckets or inclined plates secured to the inner face of the cylindrical flume between the buckets, and guiding the water, after having acted on a water-wheel, to the next, as hereinafter more fully set forth.

25 In the accompanying drawings, *a* represents a cylindrical flume, open at both ends and provided with a cross-bar, *b*, at each end, in which are the journal-bearings of a shaft, *c*, adapted to revolve in the flume. Three or more water-wheels, *A*, are arranged on and secured to the shaft *c*, preferably at equal distances apart, the planes of the wheels being perpendicular to the shaft *c*. The water-wheels *A* are constructed similarly, and each consists of an outer 30 cylindrical band, *d*, buckets *e*, each made con-

cave on one side and convex on the opposite side, and arranged spirally around the shaft, and secured at their inner edges to the shaft and at their outer edges to the inner face of the band *d*.

45 *h h* are inclined plates, secured to the flume above and below and between the water-wheels, and conduct and guide the water, after having passed through one water-wheel, to the next.

It will be seen that the water entering one 50 end of the flume will act squarely or perpendicularly against the buckets of the wheel and bear against its spirally-formed buckets, imparting a rapid revolution to the first water-wheel. The water, after passing through the 55 first bucket, is guided and forced against the second water-wheel by the inclined plates in the flume, between the first and second buckets, thence through the second water-wheel, where the operation is repeated for the third 60 water-wheel, the water finally passing out through the opposite end of the flume.

What I claim as my invention is—

1. The combination, with a flume, *a*, open at both ends, of a shaft, *c*, revolving in said flume 65 and carrying two or more water-wheels, *A*, each consisting of band *d* and spirally-arranged buckets *e*, concave on one side and convex on the other side, substantially as described, and for the purpose set forth.

2. The combination, with a flume, *a*, open at both ends, and provided with the inclined plates *h h*, of a shaft, *c*, carrying two or more water-wheels, *A*, each consisting of band *d* and spirally-arranged buckets *e*, substantially as 75 described, and for the purpose set forth.

THOMAS B. VAN PELET.
